UNITED STATES PATENT OFFICE.

WILLIAM A. RIDEOUT, SR., OF OSHKOSH, WISCONSIN.

BRAKE-SETTING MECHANISM.

No. 904,998.

Specification of Letters Patent.

Patented Nov. 24, 1908.

Application filed February 24, 1908. Serial No. 417,414.

To all whom it may concern:

Be it known that I, WILLIAM A. RIDEOUT, Sr., a citizen of the United States, residing at Oshkosh, in the county of Winnebago and State of Wisconsin, have invented certain new and useful Improvements in Brake-Setting Mechanisms; and I do declare the following to be a full, clear, and exact description of the invention, such as will enable others skilled in the art to which it appertains to make and use the same.

This invention relates to brake setting mechanism for engines or motors which are actuated by steam or electricity, and it has for its object to provide means whereby when a signal has been displayed at any point and the motor or engine is not stopped by the engineer or other person in charge, the brake setting mechanism is automatically thrown into operation; and where the car or engine is being driven by electrical power, the circuit for such power is automatically and simultaneously broken at the time that the brake setting mechanism is operated.

In the accompanying drawings, which illustrate an embodiment of the invention: Figure 1 is a diagrammatic view of mechanism by which the invention may be practiced; Fig. 2 is an enlarged side elevation of the means for automatically setting the brake mechanism in operation; Fig. 3 is a front view of said mechanism. Fig. 4 is a vertical section taken on the plane indicated by the dotted lines 4—4 of Fig. 3, and Fig. 5 is a transverse section taken on the plane indicated by the dotted lines 5—5 of Fig. 3.

Referring more particularly to the drawings, 1 indicates a car which in the present instance is shown as being electrically driven, although it can be propelled by steam or other motive power with the same results so far as brake setting mechanism is concerned.

Located adjacent to the track 2 are suitable signal stations 3, only one of which is shown, which may be of any desired construction. In each of said stations or signals a circuit closer, as a roller 4 provided with a segment 5 or other means for closing a circuit, is adapted to be actuated by the signal setting mechanism which can be driven by means of a current from line wires 6 and 7 or otherwise.

Two wires 8 and 9 are adapted to be en-

gaged by the contact or segment 5, whereby a circuit may be completed through them. 55 One of the wires, as 9, is connected with one or both of the track rails 2 and wire 8 is connected with an insulated rail 10 which is located at any point convenient to the track rails 2, it being shown midway between them 60 in the drawing, but it is evident that it could be located at either side of them with equal efficiency.

The car 1 is provided with a battery 11, of any suitable kind, one side of which is connected with the car wheels through the wire 12, and the other side is connected with a brush 13 through a wire 14. The brush 13 is adapted to engage with the third rail 10 as the car passes over it, and thereby complete a circuit through the battery if the roller 4 has been rotated so as to cause the contact 5 to engage with the wire 9 and thereby complete the circuit from wire 6 and cause the current that operates the car to set 75 the brake setting device.

As the contact 5 is never in engagement with the wires 8 and 9, except when the signal 15 is set so as to notify the engineer to stop, the circuit will never be completed 80 through the wires 8 and 9, and contact brush 13, except when it is desired that the car be stopped at the station.

To insure that the car should stop at the station when the signal is given in this manner, means are provided for automatically opening the air valve, 16, of the brake setting mechanism, 17, and thereby permit the brakes to be automatically applied and thus bring the car to a standstill. The valve 16 85 may be actuated in any desired manner, but I prefer to control it by means of a lever, 18, which is normally held against the action of a spring, 19, by a catch, as a hook, 20, on one end of a pivot lever, 21. The lever 21 is 90 adapted to be actuated to release the lever or handle 18 by means of an upward movement of the core 22 of an electro-magnet 23 which is connected with the wire 14.

By constructing and arranging the parts 100 in this manner, it is evident that as soon as a circuit is completed through the brush 13 and contact 5, the coil 23 will be energized and the core 22 moved longitudinally so as to actuate the lever 21 and thereby release 105 the handle 18 from the catch 20 when the

spring 19 will immediately throw the lever 18 forward and thus open the valve 16 and permit the application of the brake 17 in the ordinary manner. Said valve member 5 embraces a central upright casing 24 formed with upright and depending exteriorly threaded pipes or stems 25 and 26, respectively, the former being adapted for connection with a suitable source of pressure and 10 the latter with the brake or train pipe. Said casing is also provided with an obliquely disposed exteriorly threaded exhaust pipe or stem 27 to which is adapted to be screwed a relief valve 28 of any well known type or 15 pattern.

A valve member 29 is arranged to work in the casing to cut off the supply of pressure when it would be desirable to effect an application of the brakes, the relief valve being 20 regulated to permit the outflow of the pressure fluid through the exhaust pipe until the desired reduction of pressure in the train pipe has been secured to cause the application 25 of the brakes at the desired degree of pressure. Said valve member is provided with a small port 29' to allow enough of the pressure fluid to pass through to compensate for the leakage in the train pipe.

When it is desired to release the brake 30 mechanism as when it is safe for the car 1 to go forward and the contact 5 has been moved out of engagement with the wires 8 and 9 with the movement of the signal 15 the handle 18 is drawn back into engagement with 35 the catch 20 and is held in that position until after the circuit has been again completed through the battery 11 and the electro-magnet has been energized so as to release the catch 20 from the handle 18, which will again 40 cause the brake mechanism to be actuated as above described.

Where the car is electrically driven, as shown in the drawings, the handle 18 is provided with means for automatically breaking 45 the circuit from the main wire when the handle is thrown forward by the spring 19. In the drawings I have shown such means as comprising a switch member 30 secured to the handle in position for its ends to engage with the terminals 31 of the wire 32 leading from the line wire 6 to the dynamo 33, and from there to the car wheel 34 and back to the line wire 7 through the track and wire 35. The switch member 30 is preferably formed as a laminated spring of copper, with its ends adapted to be forcibly engaged with the contact points 31 of the wire 32.

By providing the handle with means for 60 automatically breaking the circuit simultaneously with the opening of the valve to control the brake mechanism, it is evident that it would be absolutely impossible for an electrically driven car to pass beyond any 65 point, or station in which means were pro-

vided for automatically closing a circuit and releasing the means for controlling said circuit and valve.

The apparatus is very simple and compact and can be applied in whole or in part to 70 any style of engine or car with but slight expense and comparatively no change in the means now provided for doing such work manually.

Having thus described my invention, what 75 I claim as new and desire to secure by Letters-Patent, is:—

1. In apparatus of the class described, a cut-off valve adapted for communication with a source of pressure fluid and the brake 80 or train pipe, a lever to hold said valve in normal position to permit the passage of the pressure fluid to the train pipe, an electric circuit including an electric magnet to release said lever, and a release valve communicating with the cut-off valve to regulate the pressure within the brake pipe after cutting off the supply of pressure to the same.

2. In an apparatus of the class specified a 90 cut-off valve adapted for communication at one end with a source of pressure fluid and at its opposite end with the brake or train pipe, a spring pressed lever connected with the cut-off valve, locking means for 95 locking the lever in normal position to permit passage of the pressure fluid through the valve to the brake pipe, an electric circuit including an electric magnet for actuating the locking means to release the lever, 100 and a relief valve communicating with the cut-off valve and adapted to be regulated to permit the escape of the pressure fluid from the brake pipe when the lever is released until the desired reduction of the 105 pressure of the fluid within the pipe has been secured.

3. In apparatus of the class specified the combination of a car, a track, a track contact, a cut-off valve on the car, an electric tripping magnet on the car, a spring pressed lever adapted to operate the valve, a latch-device for locking the lever in normal position to permit the passage of the pressure through the valve, a circuit including 115 the magnet and one rail of the track, to energize the magnet and release the lever to operate the valve to cut off the supply of pressure fluid through the same, and a relief valve communicating with the cut-off valve 120 and adapted to be regulated to permit the escape of pressure fluid from the train or brake pipe until the desired reduction of pressure of the fluid within the same is secured.

4. In an apparatus of the class described, a cut-off valve communicating with the source of pressure fluid and the train pipe, locking means to hold said valve in normal or open position to permit passage of the 130

pressure fluid to the train pipe, an electric circuit to release the locking means for the cut-off valve and a relief valve communicating with the cut-off valve to regulate the pressure within the train pipe after cutting off the supply of the pressure fluid thereto.

5 In testimony whereof I have hereunto set

my hand in presence of two subscribing witnesses.
